US0D1101748S

(12) **United States Design Patent** (10) **Patent No.:** **US D1,101,748 S**
(45) **Date of Patent:** **** Nov. 11, 2025**

(54) **NOTEBOOK COMPUTER**

(71) Applicant: **GETAC TECHNOLOGY CORPORATION**, New Taipei (TW)

(72) Inventor: **Shuan-Yeong Ju**, Taipei (TW)

(73) Assignee: **GETAC TECHNOLOGY CORPORATION**, New Taipei (TW)

(**) Term: **15 Years**

(21) Appl. No.: **29/992,145**

(22) Filed: **Mar. 6, 2025**

Related U.S. Application Data

(62) Division of application No. 29/841,525, filed on Jun. 7, 2022, now Pat. No. Des. 1,069,781.

(51) **LOC (15) Cl.** **14-02**
(52) **U.S. Cl.**

USPC **D14/315**; D14/327; D14/440

(57) **CLAIM**

The ornamental design for a notebook computer as shown and described.

DESCRIPTION

FIG. 1 is a top, front, and right side axonometric view of a notebook computer, showing my new design;
FIG. 2 is a bottom, rear, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines and any unshaded surfaces in the figures illustrate the portions of the notebook computer that form no part of the claimed design.

1 Claim, 8 Drawing Sheets
